UNITED STATES PATENT OFFICE.

HOWARD E. WATKINS, OF NEW YORK, N. Y., ASSIGNOR TO OXLEY ENOS COMPANY, OF NEW YORK, N. Y., A CORPORATION OF NEW YORK.

DESIGN FOR AN ORNAMENT FOR GAS-FIXTURES.

SPECIFICATION forming part of Design No. 36,184, dated December 30, 1902.

Application filed November 29, 1902. Serial No. 133,292. Term of patent 7 years.

To all whom it may concern:

Be it known that I, HOWARD E. WATKINS, a citizen of the United States, and a resident of New York city, borough of Manhattan, 5 county and State of New York, have invented and produced a new, original, and ornamental Design for an Ornament for Gas-Fixtures, of which the following is a specification, reference being had to the drawings accompanying 10 and forming a part of the same.

Figure 1 is a plan view of an ornament embodying this design. Fig. 2 is an elevation of the same, partly in section, along the dotted line in Fig. 1.

As indicated in the drawings, the ornament 15 comprises a central convex boss A and an outer flaring portion B, which is ornamented by the spirally-arranged separated beading

C, the pitch of this beading increasing as it approaches the edge of the ornament. Near 20 the edge of the ornament and continuing the line of the beading in each case there are arranged the separated spherical beads D, which are located in the separated flutes D, formed in the surface of the ornament. 25 These flutes correspond with the edge flutes F, which give a fluted outline to the ornament.

What is claimed as new is—

The ornamental design for an ornament 30 for gas-fixtures, substantially as shown and described.

HOWARD E. WATKINS. [L. S.]
